DESIGN FOR AN ELECTRIC FAN

Edmund W. Fruit, Chicago, Ill., assignor to
R. T. Welsh, James E. Welsh, and Edmund W.
Fruit, a partnership, doing business as J. Ed-
mund Regor Company, Rockford, Ill.

Application March 10, 1947, Serial No. 137,475

Term of patent 7 years

(Cl. D26—7)

To all whom it may concern:

Be it known that I, Edmund W. Fruit, a citizen of the United States, residing at Chicago, in the county of Cook and State of Illinois, have invented a new, original, and ornamental Design for an Electric Fan, of which the following is a specification, reference being had to the accompanying drawing, forming a part thereof.

In the drawing:

Figure 1 is a front elevational view of an electric fan, showing my new design.

Fig. 2 is a side elevational view.

Fig. 3 is a rear elevational view.

The characteristic features of my design re-

side in the portions shown by means of full lines in the drawing.

I claim:

The ornamental design for an electric fan, substantially as shown and described.

EDMUND W. FRUIT.
